UNITED STATES PATENT OFFICE.

FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

EPICYCLOIDAL GEARING.

Application filed November 29, 1920. Serial No. 427,062.

To all whom it may concern:

Be it known that I, FARNUM F. DORSEY, a citizen of the United States, residing at Rochester, in the county of Monroe and State of New York, have invented certain new and useful Improvements in Epicycloidal Gearing; and I do hereby declare the following to be a full, clear, and exact description of the invention, such as will enable others skilled in the art to which it appertains to make and use the same.

This invention relates to epicycloidal gearing of the type in which a planetary pinion or gear is supported by a rotary spider or carrier, while in engagement with two or more gears of either external or internal form.

One object of the invention is to produce a gearing in which the structure, while unusually compact, provides ample bearing surfaces for the several parts. Another object of the invention is to produce a gearing which may be readily assembled and disassembled, and which is of simple form and construction, with a minimum number of parts.

To the foregoing ends it is proposed to provide the several elements of the gearing with bearing-surfaces adapted to cooperate with the toothed surfaces of the gears and pinions, thereby dispensing with the usual journals and studs and securing the several advantages above set forth, in a manner which will be apparent from the description of the preferred embodiment of the invention.

In the accompanying drawings Fig. 1 is a side-elevation of a gearing embodying the present invention, and Fig. 2 is a horizontal sectional view, on the line 2-2 in Fig. 1. Fig. 3 is a side-elevation of a modified form of the invention, and Fig. 4 is a vertical sectional view on the line 4-4 in Fig. 3. Fig. 5 is a detail-view showing the arrangement of the gear-teeth in Figs. 1 and 2.

In Figs. 1 and 2 the invention is illustrated as embodied in a gearing of the type in which the planetary pinions revolve while in engagement with two gears differing slightly in number of teeth. Here the gears, 10 and 11, are located side-by-side, and the gear 11 is keyed to a central shaft 12. The gear 10 is keyed to a member 13 mounted loosely on the shaft. If one gear is held stationary the other will be rotated, and the

member 13 is accordingly shown as provided with an arm 14 which engages some conveniently located stationary body 15, thereby preventing rotation of the gear 10.

Two planetary pinions 16 are used in the illustrated gearing, and these pinions are actuated by a rotary carrier 17. The novelty of the invention resides particularly in the formation of these parts. The carrier is bored to bear directly on the toothed peripheries of the gears 10 and 11, and it is also bored to provide two recesses which receive and conform closely to the pinions 16. In this manner the carrier and the pinions are provided with bearings which are of large area and are axially coextensive with the toothed surfaces. All working parts and bearings are thus brought into the same planes, the parallelism of all axes is assured and rigidly maintained, and the structure is rendered more compact than is possible with any other known structure providing the same strength and the same extent of bearing-surfaces.

The planetary pinions and the carrier are retained against axial displacement in one direction by the member 18, and in the other direction by a plate 19 which may be loose on the shaft 12. The carrier is shown as provided with peripheral teeth 19 through 35 which it may be rotated, as by the worm 20 shown in the drawings. This arrangement is particularly convenient where the gearing is used to actuate an odometer or counting mechanism by power derived from a rapidly rotating shaft, such as that of a tachometer.

In an epicycloidal gearing of the type in question it is customary to provide the two gears which are to be relatively rotated with numbers of teeth differing by one, or by a very small number. While this slight difference involves a slight difference in pitch-diameter, the two gears may still cooperate satisfactorily with a single planetary pinion if the teeth are of the involute form, so that the depth of engagement need not be exact. In the gearing of the present invention it is desirable, though not necessary, to give the carrier a bearing engagement with the peripheries of both gears. In order that this may be done without the necessity of boring the carrier to two different diameters, the arrangement of the teeth on the gears is slightly modified.

The gears 10 and 11 are made both of the same pitch-diameter regardless of the fact that they have different numbers of teeth. The teeth are also of the same form and thickness, but are spaced differently. Fig. 5 is a detail-view, on a greatly enlarged scale, showing a few teeth on adjacent parts of the gears. Here the teeth 21 of the gear 10 are normal in both form and spacing, but the teeth 22 on the gear 11, while similar to the teeth 21, are spaced farther apart, so that the gear 11 has at least two less teeth than the gear 10. While it is not possible, with this arrangement, to secure theoretically correct action of the teeth, it has been found that if the gears be cut with ample back-lash they will work satisfactorily for many purposes.

Figs. 3 and 4 show the application of the invention to a gearing of the type in which the planetary pinion meshes with two gears in the same plane. Here the inner gear 23 is keyed to the shaft 24, while the outer gear 25 has internal teeth engaged by the pinion 26. The rotary carrier 27 has a cylindrical inner bearing-surface which turns on the gear 23, as in the construction previously described, and it has also a cylindrical outer surface on which, as a bearing, the gear 25 turns. The carrier is also provided with a cylindrical recess serving as a bearing for the pinion 26.

The carrier 27 is provided with a hollow extension 28 by which it may be connected with any mechanism to turn or be turned by the gearing. The several rotary members are retained against relative axial displacement by a flange 29 on the carrier, and a plate 30 mounted loosely on the shaft 24. The gear 25 is provided with external teeth, through which it may drive or be driven by means such as a pinion 31.

While the drawings show only two forms

of gearing embodying the invention, it will be apparent that it is applicable to many other types and varieties of epicycloidal gearing, within the scope of the following claims.

The invention claimed is:

1. Epicycloidal gearing comprising: a central gear with an external toothed surface; a planetary pinion meshing with the gear; and a carrier surrounding said gear and having a concentric bearing-surface closely embracing the toothed surface of the gear and an eccentric bearing-surface closely embracing the toothed surface of the pinion.

2. Epicycloidal gearing of the type comprising two coaxial gears arranged side-by-side and having different numbers of teeth, a carrier, and a planetary pinion revoluble around the axis of said gears and meshing with both of them; said gearing characterized by the fact that said gears are of equal outside diameter but different tooth-spacing and that the carrier has a cylindrical bearing-surface closely conforming to the outer surfaces of both gears, whereby the gears serve as an axial support for the carrier.

3. Epicycloidal gearing comprising: two coaxial gears arranged side-by-side and having different numbers of teeth; a carrier surrounding said gears and having a cylindrical bearing-surface conforming to the outer surfaces of the gears, whereby the gears serve as an axial support for the carrier; a planetary pinion meshing with the two gears, substantially coextensive, longitudinally, with the carrier, the carrier being provided with a recess closely embracing the pinion and constituting a bearing from end to end thereof; and two parallel end-plates independent of, but closely embracing the carrier and retaining the carrier and the pinion against axial movement.

FARNUM F. DORSEY.
